UNITED STATES PATENT OFFICE.

ARNOLD B. HOLMES, OF BOSTON, AND GEORGE F. GALE, OF WINTHROP,
MASSACHUSETTS.

KEY-SOCKET OR SWITCH FOR INCANDESCENT ELECTRIC LAMPS.

SPECIFICATION forming part of Letters Patent No. 427,514, dated May 6, 1890.

Application filed October 24, 1889. Serial No. 328,010. (No model.)

To all whom it may concern:

Be it known that we, ARNOLD B. HOLMES, of Boston, in the county of Suffolk and State of Massachusetts, and GEORGE F. GALE, of Winthrop, in the county of Suffolk and State of Massachusetts, have invented certain new and useful Improvements in Key-Sockets or Switches for Incandescent Electric Lamps, of which the following is a description sufficiently full, clear, and exact to enable any person skilled in the art or science to which said invention appertains to make and use the same, reference being had to the accompanying drawings, forming part of this specification, in which—

Figure 1 is a side elevation of our improved key-socket detached from the lamp; Fig. 2, an end elevation of the same, showing the position of the key when the circuit is closed; Fig. 3, a like view showing the position of the key when the circuit is broken; Fig. 4, a vertical transverse section shown on line xx in Fig. 3.

Like letters and figures of reference indicate corresponding parts in the different figures of the drawings.

Our invention relates especially to key-sockets for breaking and closing the electric circuit in incandescent lamps; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the socket, which consists, primarily, of a rectangular metallic post or rod screw-threaded at both ends, as best shown in Fig. 4.

A disk b, composed of hard rubber, is turned onto the end d and secured in position by a key f. A segmental disk g, also composed of hard rubber, is turned onto the opposite end h of said body and secured thereto by a key i, the threaded end h of the body projecting a sufficient distance beyond said disk to receive the lamp.

A strip of metal m, preferably phosphor-bronze, is secured to the inner face of the

disk b, its free end p being bent downward toward the disk g at an angle to the disk b. A similar strip of phosphor-bronze q is secured to the outer face of the disk g, a free end r thereof being bent upward past the straight edge t of the disk g and parallel with the free end p of the strip m.

A horizontally-arranged rubber tube v passes centrally through the body A. A key D is fitted to rotate in said tube and is provided on one end with a thumb-piece w.

A rectangular metallic holder z is disposed loosely on the opposite end of the shaft of the key D.

A rectangular block y of insulating material, preferably hard rubber, is secured in the holder z around the key-shaft D by pin j. A pin 15 on the key-shaft works loosely in a slot or groove 16 in said block. On opposite sides two edges 17 of the holder z are turned upward over the sides of the block y in position to come into contact with the free ends r p of the strips m q, said block and holder being disposed on the key-shaft between said strips.

A metallic connector 18 is secured to the disk b in contact with the bronze strip m, and is provided in its lower end with a set-screw 19. A similar connector 20, provided with a set-screw 21, is secured to the body A at the side opposite the connector 18.

In the use of our improvement the lamp is turned on the threaded end h of the body A until its filament comes into contact with the strip q. The conducting-wires are respectively secured in contact with the connectors 18 and 20 by threaded screws 19 and 21.

When the parts are in the position shown in Fig. 2, the metallic sides 17 of the holder z are in contact with the free ends p r of the strips m q, and the circuit is closed through the wires.

By turning the key D a quarter-revolution its pin 15, engaging the wall of the slot 16, forces and revolves said holder a corresponding distance, and the ends of the insulating-block y are brought into contact with the strip ends r p, the circuit being thus broken. (See Fig. 3.) The ends r p, being composed of spring metal, bear against the sides of the holder or insulating-block sufficiently hard to

prevent them from being accidentally turned. By means of the pin 15 and slot 16 sufficient play is afforded to enable the spring ends of the strips *m q* to act upon the holder and 5 complete a quarter-revolution should the key accidentally not be turned sufficiently far to effect this and prevent an arc being formed.

The holder *z* and block *y* form a rectangular cam *H* for closing and breaking the circuit 10 between the electrodes formed by the bronze strips *m q*.

The plate *q* and body *A* form the lamp terminals.

Having thus explained our invention, what 15 we claim is—

1. The combination of a short metallic center post provided with an insulating-disk at its upper end and with an insulating segmental disk at its lower end, said post having a 20 screw-threaded extension below the lower disk for receiving a lamp, a spring-electrode attached at one end to the upper disk and provided with a downwardly-extending spring-arm, a metallic plate attached to the lower face of the segmental disk 25 and provided with a spring-arm extending upward past the straight side of said disk, an insulating-sleeve extending transversely through said center post, and a rotary key within said sleeve provided at one end with a rectangular cam disposed between said 30 spring-arms, said cam having conductors on two opposite sides.

2. The combination of a short metallic center post provided with an insulating-disk at its upper end and with an insulating segmental disk at its lower end, said post having a screw-threaded extension below the lower disk for receiving a lamp, a binding-post dependent from the lower face of the upper disk, a binding-post attached to said center post, a 35 spring-electrode attached at one end to the upper disk in contact with the dependent binding-post and provided with a downwardly-extending spring-arm, a metallic plate attached to the lower face of the segmental disk 40 and provided with a spring-arm extending upward past the straight side of said disk, an insulating-sleeve extending transversely through said center post, and a rotary key within said sleeve provided at one end with a rectangular cam disposed between said 45 spring-arms, said cam having conductors on two opposite sides.

ARNOLD B. HOLMES.
GEORGE F. GALE.
